DOWELING JIG

Bernard L. Polkosnik, Bridgeport, Conn., assignor
to General Hardware Mfg. Co. Inc., New York,
N. Y., a corporation of New York

Application November 15, 1949, Serial No. 6,057

Term of patent 14 years

(Cl. D54—14)

To all whom it may concern:

Be it known that I, Bernard L. Polkosnik, a citizen of the United States, residing in the county of Fairfield, city of Bridgeport, and State of Connecticut, have invented a new, original, and ornamental Design for Doweling Jigs, of which the following is a specification, reference being had to the accompanying drawings, forming part thereof, wherein Fig. 1 is a perspective view of a doweling jig embodying my new design; and Fig. 2 is a perspective view of the end component at the extreme right in Fig. 1.

I claim:
The ornamental design for a doweling jig, substantially as shown.

BERNARD L. POLKOSNIK.
